(57) **CLAIM**

We claim the ornamental design for a computer display with a graphical user interface, as shown and described.

DESCRIPTION

The file of this patent contains a least one drawing executed in color. Copies of this patent with color drawings will be provided by the United States Patent and Trademark office upon request and payment of the necessary fee.

FIG. 1 is a front elevational view of a computer display with a graphical user interface showing our new design; and, FIG. 2 is an enlarged view thereof, but shown without the broken lines for clarity of illustration.

The broken-line drawing of a computer display in FIG. 1 is for illustrative purpose only and forms no part of the claimed design.
